DETACHABLE SUPPORTING MEANS

Herman H. Lowenstein, Chicago, Ill.

Application March 30, 1938, Serial No. 198,980

3 Claims. (Cl. 40—124)

The present invention relates generally to a novel and improved means for detachably supporting on a sheet member a plurality of elements, said attaching means being formed integral with said supporting sheet.

It is an object of this invention to provide as an article of manufacture a sheet member formed of a pliable material capable of having tongues die-cut therein by means of which tongues suitable elements may be supported on said sheet member in detachable engagement therewith.

Another object of this invention is to provide a sheet member of suitable material, such as cardboard or the like, said member being adapted for supporting thereon a plurality of elements, said elements being held in place on the member by means of slots cut therein cooperating with tongues die-cut in the sheet member, whereby said elements may be readily attached to or detached from said supporting member.

A further object of this invention is to provide in a device of the character described, novel and improved means for supporting a plurality of elements on a sheet member of pliable material, which means include die-cutting suitable tongues in the sheet member, said tongues being adapted for engagement by portions of said elements to be held thereon, whereby said elements may be detachably supported on said sheet member.

A still further object of this invention is to provide a device of the character described comprising a sheet member of pliable material capable of having tongues die-cut therein, said tongues being arranged in a plurality of rows, and each of said tongues being adapted for detachably supporting on said sheet member an element, such as a medallion or the like, each of said elements having a slit cut therein for engagement with a tongue on the sheet member and said elements being adapted for having desired information inscribed thereon.

A still further object of this invention is to provide a device of the character described which will be simple in construction and assembly, which may be produced along lines convenient for low-cost manufacture, and which will, at the same time, be highly efficient for carrying out the purposes for which it is designed.

With the foregoing and other objects in view which will appear as the description proceeds, the invention consists in certain novel features of construction, arrangement and combination of parts hereinafter fully described, illustrated in the accompanying drawing, and particularly pointed out in the appended claims, it being under-

stood that various changes in the form, proportion, size and minor details of the structure may be made without departing from the spirit or sacrificing any of the advantages of the invention.

For the purpose of facilitating an understanding of my invention, I have illustrated in the accompanying drawing, a preferred embodiment thereof, from an inspection of which, when considered in connection with the following description, my invention, its mode of construction, assembly and operation, and many of its advantages should be readily understood and appreciated.

Referring to the drawing in which the same characters of reference are employed to indicate corresponding or similar parts throughout the several figures of the drawing:

Fig. 1 is a top plan view of a plaque or supporting sheet having a plurality of elements supported thereon;

Fig. 2 is a fragmentary portion of a plan view of a similar sheet showing elements of a shape different from that shown in Fig. 1 supported thereon;

Fig. 3 is a sectional view through the detachable fastening means between the element and its supporting sheet taken substantially on line 3—3 of Fig. 1;

Fig. 4 is a modified form of fastening means employed for securing the element to a supporting sheet;

Fig. 5 is a sectional view taken on line 5—5 of Fig. 4;

Fig. 6 is a still further modified form of fastening means for securing the element to its supporting sheet;

Fig. 7 is a sectional view taken substantially on line 7—7 of Fig. 6.

Stated generally, the present invention involves the idea of producing a supporting sheet made up of a pliable material which readily lends itself to die-cutting, which sheet is provided with a plurality of die-cut tongues upon which may be supported suitable elements of any desired shape or size, which elements may carry either a portrait or a picture, or other insignia. By assembling these elements on the plaque, the entire plaque may be built up to illustrate, for example, the several species of animals belonging to the same family, these elements being removed from or added to the plaque from time to time.

Another example of its use might be the production of a plaque upon which the portraits of the Presidents of the United States may be mounted, each element having a portrait of a President, said elements being mounted on said

plaque in the manner to be hereinafter more fully illustrated, and when the entire plaque has been completed, the same may be supported on a wall or the like.

5 Referring to the drawing more specifically by characters of reference, the numeral 10 designates generally a sheet member formed of pliable material, such, for example, as cardboard, Celluloid, or other material that lends itself readily 10 to die-cutting. Said sheet member may be formed of any suitable size and shape and may be provided adjacent its upper end with suitable openings 11, to which may be attached the ends of a flexible member such as a cord or the like. The member 10 has die-cut therein a plurality of tongues 12, which tongues may be arranged in horizontal rows as shown in Fig. 1, and by means of which there may be detachably 15 supported on said sheet member 10 the elements 13, which elements are also formed of suitable pliable material such as cardboard, Celluloid or the like. Each of the elements 13 may be provided with a suitable tab 14 adjacent its upper end 20 25 which is die-cut, as shown at 15, to provide a slit 16, said slit permitting the passage therethrough of the tongue 12, as shown more clearly in Fig. 3, thereby supporting the element in place on the sheet 10. As shown in the drawing, the element 13 may be formed of any suitable size and shape, and when in assembled position with the supporting sheet 10, will lie substantially flat thereagainst. The element 13 is adapted to have provided thereon either a picture or a portrait or 30 35 any other suitable insignia, which inscription will bear some relation to the inscriptions appearing or provided on the other elements carried by each supporting member. Thus, for example, the plaque illustrated in Fig. 1 may be used for the purpose of carrying the portraits or pictures of baseball players of a certain baseball team, each element 36 being provided with a picture or a portrait of one of the players of said team, and as these players change from time to time, 40 45 these elements may be removed and a new element inserted in its place, so that the make-up of that particular baseball team may be kept up-to-date at all times.

The modification shown in Fig. 2 is substantially the same in construction as that shown in Fig. 1, except that the elements 13 are illustrated as circular instead of rectangular. In Fig. 4, however, the means for attaching the elements 20 to the supporting sheet 10 is somewhat different from that illustrated in Figs. 1 and 2 in that the sheet member 10 is die-cut to produce a pair of oppositely disposed triangular tongues 21, between which may be received the end edges of the element 20.

60 In Fig. 6 the supporting sheet 10 is provided with openings 25 spaced from each other a dis-

tance equal to the length of the element 26, said element being provided with tongues 21, which tongues are adapted to be disposed within the openings 25, as shown in Fig. 6 for detachably securing the element 26 to the supporting member 10.

From the above, it will be readily apparent that I have provided a device which will be highly useful for several purposes, educational as well as entertaining. It will also be noted that the 10 device may be simply constructed and at a low cost.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

I claim:

1. In combination with a sheet member of pliable material, insignia bearing elements, a series of tongues die-cut in said sheet member, and a tab die-cut in each of said insignia bearing elements and pressed out therefrom to present a substantially semi-circular slit for receiving one of the tongues provided on said sheet member 30 to support the said insignia bearing element on said sheet member.

2. In combination with a sheet member of pliable material, insignia bearing elements, a series of tongues die-cut in said sheet member, said tongues being of substantially increasing flaring diameter from approximately half the distance from the tip to the base, and a tab die-cut in each of said insignia bearing elements and pressed out to present a substantially semi-circular slit, each of said tongues being adapted for disposition within the slit of one of said insignia bearing elements, said tongues and slits co-operating to produce a positive binding engagement by reason of the flaring size of said tongues 45 engaging the edges of its co-operating slit in the insignia bearing element.

3. In combination with a sheet member of pliable material, insignia bearing elements, a series of tongues of die-cut in said sheet member, said tongues being of substantially increasing flaring diameter from part of the distance from the tip to the base, and a tab provided in each of said insignia bearing elements and pressed out to present a substantially semi-circular slit, the diameter of said slit being less than the larger diameter of the base of said tongue whereby a binding engagement will be produced between the tongue and its co-operating slit when the said tongue is inserted through the slit.

HERMAN H. LOWENSTEIN. 60
